David L. Principe**CLAIM**

The ornamental design for a baby food container, as shown and described.

DESCRIPTION

FIG. 1 is a front perspective view of the baby food container showing our new design;

FIG. 2 is a rear perspective view thereof;

FIG. 3 is a right side elevational view thereof, the left side elevational view thereof being a mirror image of the view shown;

FIG. 4 is a top plan view thereof;

FIG. 5 is bottom plan view thereof; and,

FIG. 6 is a partial cross-sectional view taken along lines 6-6 of FIG. 3.

The dot-dot-dash broken lines in the FIG. 6 cross-section view define the bounds of the claim in that view and form no part thereof.
